INVENTOR:

Thomas E. Hunt
By John Howard Mulligan
HIS ATTY.

UNITED STATES PATENT OFFICE.

THOMAS E. HUNT, OF CHICAGO HEIGHTS, ILLINOIS, ASSIGNOR TO QUAKER MANUFACTURING COMPANY, OF CHICAGO, ILLINOIS, A CORPORATION OF ILLINOIS.

IRONING MACHINE.

Application filed July 7, 1921. Serial No. 482,921.

To all whom it may concern:

Be it known that I, THOMAS E. HUNT, a citizen of the United States, and a resident of Chicago Heights, in the county of Cook 5 and State of Illinois, have invented certain new and useful Improvements in Ironing Machines, of which the following is a full, clear, and exact specification.

My invention is concerned with ironing 10 machines, and is designed to produce a device of the class described, which shall be extremely simple in construction, withal effective in its operation, and which cannot readily get out of order. To these ends, 15 it consists of certain novel features and combinations of elements, all as will be fully described in the specification and particularly pointed out in the claims.

It is further concerned with ironing 20 machines driven by a motor and so constructed that it is impossible to allow the cloth covered roll to stop its rotation while it is in contact with the heated shoe, which would burn the cloth on the roll if it were at rest.

25 To this end I place in the circuit of the motor that rotates the roll a switch which cannot be opened while the roll is in contact with the shoe, and which is automatically closed when the roll and shoe are moved 30 into said contact.

My invention is further concerned with a novel automatic latch mechanism for securing the shoe and holding it when it is moved away from the roll.

35 My invention is finally concerned with a novel adjustment of the concave shoe relative to the roll so that they can be made to register exactly upon assembly of the parts, even if there should be some inaccuracy in 40 their construction.

To illustrate my invention, I annex hereto three sheets of drawings in which the same reference characters are used to designate identical parts in all the figures, of which—

45 Fig. 1 is a perspective view of an ironing machine embodying my invention;

Fig. 2 is a central transverse vertical section upon a larger scale;

50 Fig. 3 is a top plan view of one edge of the feed table showing the motor switch and its co-operating safety lever;

Fig. 4 is an end elevation of the roll showing its adjustment;

55 Fig. 5 is a section on the line 5—5 of Fig. 2 showing the adjustment for the shoe;

Fig. 6 is a view of the various elements shown in Fig. 5 disassembled more clearly to show their construction;

Fig. 7 is a front elevation of the same elements assembled; 60

Fig. 8 is an end elevation of the machine, but with the shoe dropped away from the roll, and a portion of the framework broken away and in section; and

Fig. 9 is a top plan view of one corner of 65 the ironing board showing the switch.

In carrying out my invention in its preferred form, I employ two symmetrical end frame pieces or castings 10, which are firmly secured together by the four rods or tubes 70 11 in a customary manner. Journaled in suitable boxes 12, one of which is seen in Fig. 4, are the bearing pintles 13 for the metallic roller 14, which has wound thereon one or more layers of fabric 15 which in 75 operation is in contact with the concave surface of the metallic plate 16 constituting the engaging surface of the shoe. In order to adjust the position of the roll 14 to and from the shoe, I mount the boxes 12 in the bearing slots 17 formed in the goose-neck top of the frame pieces 10 and provide the set-screw 18 having a head co-operating with the T-shaped recess 19 in the box and threaded through the top piece 20 secured 80 over the bearing slots 17. To rotate the roll, I employ a small electric motor 21 which is suspended from the base plate 22 which is supported by a plurality of hooks 23 from the upper pair of rods and sleeves 85 11, as clearly shown in Figs. 1 and 2. The armature shaft of the motor has secured on its outer end the belt pulley 24 which is connected by the belt 25 with the belt wheel 26 secured on the outer end of the worm shaft 27 journaled in a suitable bearing 28 secured to the adjacent frame piece 10 and having secured thereon the worm 29 which meshes with the worm gear wheel 30 journaled on the bearing stud 31 projecting 90 outward from associated end piece 10. The worm wheel 30 has secured thereto, or formed integrally therewith, the sprocket pinion 32 which drives the sprocket wheel 33 secured on the adjacent bearing pintle 105 13 of the roll 14 through the medium of the sprocket chain 34.

The shoe plate 16 is secured upon the edge portions of the pair of supporting levers 35, said portions having a shape corresponding 110

to the internal cross section of the shoe plate, which levers are journaled on the inside of the frame pieces 10 by the adjustable connections best shown in Figs. 2, 5, 6 and 7, 5 where it will be seen that each of the frame pieces 10 has projecting inwardly therefrom the bearing pintle 36 which extends through an aperture 37 in the lever 35, which aperture is considerably larger than the pintle 36 so that the position of the lever 35 may 10 be adjusted relative to the pintle 36, which forms the actual bearing for the lever through the adjusting piece 37^a which is shaped to fit in the elongated recess formed 15 by the pair of inwardly extending ribs 38 formed on the face of the adjacent portion of the lever 35. This adjusting piece 37 has the bearing aperture 39 which forms the actual bearing on the pintle 36, and it also 20 has the elongated slot 40 therein through which passes the set-screw 41 which is threaded into an aperture in the lever 35 and has its head bearing against the washer 42. By means of the connections here de- 25 scribed, it will be obvious that the position of the lever 35 can be adjusted longitudinally relative to the bearing pintle 36, so as to bring the shoe 16 into exact register with the roll 14, even if the parts should not be 30 constructed so as to fit with extreme accuracy.

The lower end of each of the levers 35 is provided with the aperture 43 in which is hooked one end of the strong helically 35 coiled contractile spring 44, the other end of which has secured therein the bolt 45 which extends through an aperture in the inwardly projecting lug 46 formed on the frame casting 10, and the spring is placed 40 under the desired tension to cause the shoe to press against the roll with the desired force by turning the wing nut 47 on the bolt 45.

The upper ends of the levers 35 are shaped 45 so as to have the wooden feed table 48 secured thereon in the proper position so that work can be passed across the feed table and caught between the shoe and the roll to start the operation of ironing when the shoe 50 is swung back a little from the roll. To control the position of the shoe relative to the roll and at the same time leave the operator's hands entirely free, I provide the treadle bar 49, extending the length of the 55 machine, and secured upon the outer ends of the pair of treadle levers 50, which are secured upon the rock shaft or sleeve 51 which is journaled on or in the projections 52 of the end pieces 10. The treadle is connected to the levers 35 by means of a pair 60 of links 53, which links are jointed at 54, so that when it is desired to drop the shoe entirely away from the roll, as indicated in full lines in Fig. 8 and in dotted lines in 65 Fig. 2, this can be effected by screwing the

wing nuts 47 entirely off of the bolts 45, when the levers 35 will be relieved from the spring tension tending to hold the shoe up against the roll. When this is done, the treadle drops to the dotted line position 70 shown, but if the links 53 were not jointed at 54, so that they could assume the position shown in full lines in Fig. 8 and in dotted lines in Fig. 2, the levers 35 could not swing away from the roll to the extent shown, because the treadle 49 would engage the floor 75 and stop its movement. When, however, the joint 54 breaks, as shown in Fig. 2, this difficulty is obviated.

To lock the shoe automatically a short 80 distance away from the roll, I provide the locking lever 55, which has its upper end extending up by one end of the feed table 48 and is fulcrumed to the adjacent treadle lever 50 at 59. This lever is provided with 85 a recess 60 adapted to accommodate the projection 46 and having the square shoulder 61, adapted to catch the square lower edge of the projection 46 when the lever is drawn down far enough by the depression of the 90 treadle 49. Automatically to throw the lever 55 over to engage the catch when it is depressed, I pivot upon it at 62 an over-weighted dog 63 which has its nose 64 always in engagement with the adjacent edge 95 of the end casting 10, as clearly seen in Fig. 1. The overweight of this dog 63 always serves to throw the lever forward to insure its catching, thus obviating the necessity of employing a spring such as is ordinarily used for this purpose. When the shoe is to be returned in contact with the roll, all that is necessary is to shove the lever 55 backward enough to disengage the catch, when of course the springs 44 carry 100 the shoe into engagement with the roll.

To prevent the possible burning of the cloth 15 on the roll by the heated shoe, if the shoe should be at rest when the shoe is in engagement therewith, I lead the wires 110 64 supplying the current for the motor to a switch 65 which is preferably set in the adjacent end of the table 48, and has the short operating lever 66 projecting from the edge of the feed table 48 into the path of the up-turned end 67 of the safety lever 68 which is fulcrumed at 69 to the adjacent lever 35. The downwardly extending arm 70 of this lever 68 has the set-screw 71, seen in full lines in Fig. 8 and in dotted lines in Fig. 2, threaded therethrough and held in the desired position of adjustment by the lock nut 71^a threaded thereon and co-operating with the end of the lever. The end of the set-screw 70 is always in contact with the edge 115 portion 72 of the adjacent end casting 10, as seen in Figs. 1 and 8, and the set-screw 70 is so adjusted that when the shoe is in contact with the roll, the safety lever 68 is forced up into the position shown in Figs. 1 120 and 8. The safety lever 68 is connected to the treadle 49 by a link 73, which link is jointed at 74 to the treadle lever 50, so that when the treadle 49 is forced up, the safety lever 68 is forced up into the position shown in Figs. 1 125 and 8.

and 3, where the inner edge of the portion 67 of the lever engages the switch lever 66 and forces it to the position shown in Fig. 3, where the switch is closed, and the motor is 5 energized and necessarily rotates and drives the machine. As soon as the shoe is swung far enough away from the roll so that there is no danger of burning it if the roll is at rest, the safety lever 68 swings 10 away from the switch lever 66, as seen in dotted lines in Fig. 2, and the operator can then throw the switch lever 66 to stop the motor, which however, will be automatically started again, as soon as the shoe is released 15 and the springs 44 are allowed to carry it back into engagement with the roll.

The shoe 16 is heated by the customary pipe burner 73, and this burner is enclosed by a sheet metal casing 74 secured at its 20 edges to the shoe 16 and having the sets of perforations 75 and 76 through the length thereof at the bottom and top to furnish air for combustion. To shield the feed table 48 and the operator somewhat from the 25 heat, I place above the casing 74, and connect at its upper edge to the shoe 16, the sheet metal shield 77 which has its ends secured to the levers 35 by the bolts 78, as seen in Fig. 1.

30 A convenient receptacle for the clothes after they are ironed is formed by the sheet metal trough 79 which is supported beneath the roll and the shoe by the pair of cross pieces 80 which have the feet 81 extending 35 downward therefrom and terminating in the yokes 82 embracing the rods and tubes 11 to removably support the trough.

The operation of my improved ironing machine will be apparent from the foregoing 40 description of its construction and intended mode of operation.

While I have shown and described my invention as embodied in the form which I at present consider best adapted to carry out 45 its purposes, it will be understood that it is capable of modifications, and I do not desire to be limited in the interpretation of the following claims except as may be necessitated by the state of the prior art.

50 What I claim as new and desire to secure by Letters Patent of the United States is:

1. In an ironing machine, the combination with a supporting frame, of a pair of levers fulcrumed therein, a heated shoe rigidly secured between the levers so as to move therewith; a feed table secured between the levers just beyond the shoe, a roll journaled in the frame co-operating with the shoe, means for rotating the roll, an arm connected with one of the levers and projecting downwardly from the shoe, and a spring connected at one end to the arm and at the other to the frame to pull the shoe against the roll.

2. In an ironing machine, the combination 65 with a supporting frame, of a pair of levers fulcrumed therein, a heated shoe rigidly secured between the levers so as to move therewith, a feed table secured between the levers just beyond the shoe, a roll journaled in the frame co-operating with the shoe, means for rotating the roll, a spring connected to one of the levers to hold the shoe against the roll, and means to draw the shoe from the roll against the resistance of the 70 spring.

3. In an ironing machine, the combination 75 with a supporting frame, of a heated shoe pivoted therein, a roll journaled in the frame co-operating with the shoe, means for rotating the roll, a pair of helically coiled contractile springs connected to the pivoted shoe at its ends at a distance from its fulcrum and serving to pull the shoe toward the center of the roll, a pair of bolts connected to the other ends of the springs and passing through apertures in the frame, and set nuts on the bolts on the outside of the frame so that when the latter are removed the shoe 80 can drop away from the roll.

4. In an ironing machine, the combination 85 with a supporting frame, of a heated shoe mounted thereon, a feed table projecting outwardly from the top of the shoe, a sheet metal covering for the shoe, a burner between the heated shoe and the cover, and a heat deflecting plate extending from the shoe between the cover and the feed table.

5. In an ironing machine, the combination 90 with a supporting frame of a heated shoe pivoted therein, a roll journaled in the frame co-operating with the shoe, means for rotating the roll, a pair of helically coiled contractile springs connected to the pivoted shoe at its ends, a pair of bolts connected to the other ends of the springs and passing through apertures in the frame, set nuts on the bolts outside of the frame, a treadle, and jointed links connecting the treadle with the shoe so that when the nuts are removed, the shoe is free to drop away from the roll despite the contact of the treadle with the 95 floor.

6. In an ironing machine, the combination 100 with a supporting frame, of a heated shoe pivoted therein, a roll journaled in the frame co-operating with the shoe, means for rotating the roll, springs detachably connected to the shoe and to the frame, a treadle, and jointed links connecting the treadle and the shoe so that when the springs are detached the shoe may fall away from the roll despite the contact of the treadle with the floor.

7. In an ironing machine, the combination 115 with a supporting frame, of ironing members carried thereby comprising a heated shoe and an opposed roll mounted so as to be relatively movable to and from each other,

means for rotating the roll, a foot treadle having a limited movement, and connections from the treadle to the ironing members whereby the depression of the treadle separates the members, said connections including a two-part link jointed so that the ironing members may be separated farther than the limited movement of the foot treadle will permit by breaking the joint.

10. 8. In an ironing machine, the combination with a frame, of a roll journaled therein, a second frame, a heated shoe carried by the second frame, means for moving one frame to and from the other to cause relative movement of the shoe and roll to bring them into and out of engagement, a motor for rotating the roll, a manually operable switch for the motor carried by the moving frame, and means for automatically closing said switch by the movement of the frame which brings the shoe and roll into contact.

9. In an ironing machine, the combination with a frame, of a roll journaled therein, a second frame, a heated shoe carried by the second frame, means for moving one frame to and from the other to cause relative movement of the shoe and roll to bring them into and out of engagement, a motor for rotating the roll, a manually operable snap switch for the motor carried by the moving frame, an operating lever for the snap switch, and means for swinging the lever.

10. 10. In an ironing machine, the combination with a frame, of a roll journaled therein, a second frame, a heated shoe carried by the second frame, means for moving one frame to and from the other to cause relative movement of the shoe and roll to bring them into and out of engagement, a motor for rotating the roll, a manually operable snap switch for the motor carried by the moving frame, and an operating lever for the snap switch dropped out of engagement therewith as the frame is moved to separate the roll and shoe, and contacted by the stationary frame to close the switch as the frame is moved to bring them together.

11. 11. In an ironing machine, the combination with a frame, of a roll journaled therein, a second frame, a heated shoe carried by the second frame, means for moving one frame to and from the other to cause relative movement of the shoe and roll to bring them into and out of engagement, a motor for rotating the roll, a manually operable snap switch for the motor carried by the moving frame, an operating lever for the snap switch dropped out of engagement therewith as the frame is moved to separate the roll and shoe, and contacted by the stationary frame to close the switch as the frame is moved to bring them together, and

means for adjusting the relative position of the parts at which the contact occurs.

12. In an ironing machine, the combination with a main frame, of a roll journaled in said frame, a motor, gearing from the motor to the roll, a swinging frame pivoted on the main frame, a heated shoe carried by the swinging frame, a switch in the motor circuit, and a bell crank lever pivoted on the swinging frame having one end adapted to engage and operate the switch if it is open when the other end engages a stop on the main frame.

13. In an ironing machine, the combination with a main frame, of a roll journaled in said frame, a motor, gearing from the motor to the roll, a swinging frame pivoted on the main frame, a heated shoe carried by the swinging frame, a switch in the motor circuit, a bell crank lever pivoted on the swinging frame having one end adapted to engage and operate the switch if it is open when the other end engages a stop on the main frame, and a set-screw in the last mentioned end of the lever adjustable to determine in what position of the swinging frame the switch shall be closed.

14. In an ironing machine, the combination with a frame having a pair of opposed bearing pintles, of a pair of bearing pieces journaled on the pintles, a pair of swinging frame levers radially adjustable on the bearing pieces, a heated shoe and a roll carried by the frame levers and the frame, said shoe and roll being relatively movable by swinging the frame levers.

15. In an ironing machine, the combination with a frame having a pair of opposed bearing pintles, of a pair of bearing pieces journaled on the pintles, a pair of swinging frame levers radially adjustable on the bearing pieces, a heated shoe carried by the frame levers, a roll journaled in the frame, means for rotating the roll, and means for adjusting the roll in a line substantially at right angles to the radial line of the frame levers.

16. In an ironing machine, the combination of a frame, of a pair of swinging frame levers journaled on the frame, a concave shoe carried by the frame levers, means for adjusting the bearings of the frame levers, a roll journaled in the frame co-operating with the shoe, and means for adjusting the roll bearings substantially at right angles to the adjustment of the frame lever bearings.

In witness whereof, I have hereunto set my hand and affixed my seal this 24th day of June, A. D. 1921.

THOMAS E. HUNT. [L.S.]

Witness:

JOHN HOWARD McELROY.
